UNITED STATES PATENT OFFICE.

OTIS R. HINCHER, OF SEATTLE, WASHINGTON, ASSIGNOR TO PUGET SOUND PAPER BOX CO., OF SEATTLE, WASHINGTON, A CORPORATION OF WASHINGTON.

PAPER-BOX MACHINE.

1,287,312.

Specification of Letters Patent. Patented Dec. 10, 1918.

Application filed July 3, 1917. Serial No. 178,362.

To all whom it may concern:

Be it known that I, OTIS R. HINCHER, a citizen of the United States, residing at Seattle, in the county of King and State of Washington, have invented certain new and useful Improvements in Paper-Box Machines, of which the following is a specification.

This invention relates to the manufacture of paper boxes and, more particularly, to candy boxes having top and bottom elements which extend as flanges from the cover or body members of a box.

The object of the present invention is the provision of improved means for securing the referred-to type of top or bottom elements to the box sections in a more efficient and expeditious manner than hitherto, to produce a neat-appearing and substantial box structure.

With these ends in view, the invention consists in the novel construction, adaptation and combination of devices, as will be hereinafter described and claimed.

The invention is illustrated in the accompanying drawings, in which—

Figure 1 is a view in rear elevation of a machine embodying my invention. Fig. 2 is an end elevation of the same. Fig. 3 is a sectional view through 3—3 of Fig. 1 with parts omitted. Figs. 4 and 5 are sectional views through 4—4 and 5—5 of Fig. 1 illustrating the respective cams and the parts actuated thereby but in operative positions different from those in which they are represented in Fig. 1. Fig. 6 is a sectional view taken substantially through 6—6 of Fig. 2. Figs. 7 and 8 are detail elevational views to an enlarged scale to illustrate the action of a folding and pressure-block with respect to the work which, for clearness, is shown in section. Fig. 9 is a transverse sectional view through one of the referred-to blocks and the supporting connections therefor. Fig. 10 is a perspective view of a box body. Fig. 11 is a similar view of a box bottom member; and Fig. 12 is a similar view showing the box body and bottom connected through the instrumentality of an attaching paper as effected by the present invention.

The reference numeral 15 represents the machine frame which may be of any suitable shape or construction. Journaled in bearing boxes of the frame is a transversely

arranged cam shaft 16 which is intermittently rotated from a power-driven shaft 17 through the medium of mechanism such, for example, as illustrated in Figs. 1 and 2; said mechanism includes a clutch having a member 18 adapted to be moved into engaged position with respect to its companion member by means of an operatively connected foot pedal 19.

Fixedly secured to said cam shaft are cams, indicated by 20, 21, 22 and 23, adapted to impart movements to the various associated operative parts of the machine.

Mounted for vertical reciprocatory movements in a guide 24 of the frame is an upright bar 25 having a flanged lower extremity 25¹ to which is detachably connected, as by bolts 25², a form 26 of a size to fit into the box-body A, Fig. 10. The bar 25, as shown, is connected by a link 27 to a lever 28 fulcrumed at 29 to a bracket support 15¹ of the frame and operatively connected by a rod 30 to an arm 31 of a second lever (Fig. 2) fulcrumed at 32. The other arm 31¹ of said second lever carries, preferably, a roller 33 to track upon the periphery of the cam 20 which serves in each complete rotation of the cam shaft to present the form 26 at various elevations and in opposition to the combined weight of the bar and the parts associated therewith.

Movable vertically in a guide 34 provided on the frame and in axial alinement with the bar 25 and form 26, is a post 35 having at its upper end a detachable platen 36 of length and width slightly greater than the corresponding dimensions of the box-top B, Fig. 11. Said post is connected by a link 37 (Fig. 3) with the arm 38 of a lever fulcrumed at 39 and carries on its other arm 38¹ a roller 40 which tracks on the cam 21 which is characterized by having in its periphery two concentric arcs 21¹, 21² at different radial distances from the shaft axis for the purpose of maintaining the post 35 during portions of each rotation of the cam shaft.

Positioned upon members 15² and 15³, respectively, of the machine frame, are longitudinally and transversely disposed supports 41 and 41¹. Secured to the supports 41 are attachments 42 having spaced apertured arms 42¹ in which are journaled trunnions 43 provided on the ends of transversely ar-

- ranged blocks 44, the latter having intermediate their lengths lever arms 44¹ which are connected by links 45 with a coupling bar 46 which, in turn, is connected by a link 5 47 (Fig. 6) with an arm 48 of a lever which is fulcrumed at 49 and carries by its other arm 48¹ a roller 50 which tracks on the periphery of the cam 22. The periphery of this cam, as shown in Fig. 4, is provided 10 with a circular part 22¹ concentric to the cam axis and extending approximately three-fourths of a complete circle, and with a peripheral part 22² of the cam portion 22³ which protrudes from such circular part. 15 Slidably mounted upon the blocks 44 are rectangular casings 51 (Fig. 9), each being connected to the respective block by bolts 52 secured to the casing and extending through holes, such as 44², in the block to 20 receive on their threaded protruding ends nuts 53 for regulating the extent of separation of the respective casing and supporting blocks due to the action of interposed springs 54. 25 Attachments 55 having apertured arms 55¹ are likewise secured to the transverse supports 41¹ for tiltably holding blocks 57 by trunnions 56 provided thereon; these blocks, like the aforescribed blocks 44, are provided 30 with lever arms 57¹ and connected by links 58 with a coupling bar 59, the latter being connected by a link 59¹ (Fig. 5) with an arm 60 of a lever fulcrumed at 61 and carrying a roller 62 to track against the 35 periphery of the cam 23. This cam is formed at diametrically opposite sides with arcs 23¹ concentric to the cam axis and, between the adjacent extremities of such arcs, at diametrically opposite sides, is provided 40 with protuberances 23². Similarly to what is shown in Fig. 9 with respect to the blocks 44, the blocks 57 have slidably mounted thereon casings 63 (Figs. 7 and 8) which are each yieldingly held by 45 means of springs 64 in its outermost position with respect to the block 57 therefor. The supports 41, 41¹ are arranged to be regulated to present the casings 51, 63 and the respective blocks therefor, closer to or 50 farther from the axis of the form 26 and platen 36 according to the size of the latter required in a particular run of work. When properly adjusted, said supports are secured as by means of clamping screws. 55 The operation of the invention may be explained as follows: The operator standing in front of the machine places a box top B upon a piece of attaching paper C having upon its upper 60 surface a coating of paste. This paper, as indicated by broken lines in Fig. 11, is somewhat larger than said top to furnish a projecting part outside of each edge of the top. The operator then inserts the top and 65 attached paper into the space between the

casings 63 when occupying the positions in which they are represented in Fig. 3, and when the platen is in its uppermost position as shown in this view.

The space between said casings is, however, only sufficient to accommodate the thickness of the paper in addition to the width of the top; hence the side edges of the paper are turned up, as indicated by C¹ in Fig. 7. 75

The operator places a box body A upon the form 26 to be brought down therewith onto the top, whereupon the cam 23 effects the elevation of the coupling bar 59 and the links 58, thereby acting through the medium of arms 57¹ to tilt the blocks and associated casings 63 into the positions in which they are shown in Fig. 5, resulting in the paper margins C¹ at each side of the box being folded at C² and C³, as illustrated 80 in Fig. 8, and causing, moreover, the paper to be pressed firmly against the opposing surfaces A¹, B¹ (Fig. 7) of the body and top, to insure the paper being reliably and smoothly pasted thereto. 90

When this has been accomplished, the cam 23 turns into position whereat the casings 63 tilt outwardly to occupy the positions in which they are shown in Fig. 3; the cams 20 and 21 thereupon act in concert to allow 95 the form and platen to lower the work into position to have the ends of the paper C be acted upon by the casing 51 to suitably fold the paper and press such ends against the upper surfaces of the protruding ends of the top, and also against the adjacent ends of the body A. The cam shaft continuing to rotate, then causes the cam 21 to again elevate the platen 36 and the superposed form 26 into positions whereat the casings 100 63 are again influenced to press down any hummocks obtaining at the corners of the box, and to give the overlapping portions of the paper a practically smooth and neat appearance; the casings 63 are then tilted outwardly to free the work and allow the same to be withdrawn from the form 26 as the latter ascends during the termination of a cycle of the machine's operation. 110

The several cams, as shown, are arranged 115 to impart lifting movements upon the mechanisms that actuate the form, platen and several casings in the performance of their respective duties and in opposition to the weights thereof, which serve to restore said form, platen and casings into their retractile or inoperative positions.

Springs, however, may obviously be utilized to facilitate such inoperative movements. 125

The construction and operation of the machine will, it is thought, be understood from the foregoing description.

What I claim, is—

1. In a paper box machine, the machine 130

- frame, a platen, a form, means to successively effect vertical reciprocatory movements of said platen and form intermittently and in unison with each other, devices tiltably mounted on said frame at different elevations, and mechanism to effect the operation successively of the upper and lower of said devices substantially as and for the purposes described.
2. In a paper box machine, the machine frame, vertically movable platen and form members, two pairs of blocks tiltably connected to the frame at different elevations, a casing movably connected to each of said blocks, means to limit the movements of said casings relative to the respective blocks, resilient means tending to yieldingly retain the casings in their outermost positions with respect to the associated blocks and means to effect the tilting action of the upper and lower of said blocks and the associated casings when the platen and form are at corresponding elevations.
3. In a paper box machine, the machine frame, vertically movable platen and form members, two pairs of blocks tiltably connected to the frame at different elevations, means to regulate the horizontal positions of said blocks with respect to the axis of movement of said platen and form, a casing movably connected to each of said blocks, means to limit the movements of said casings relative to the respective blocks, resilient means interposed between the respective blocks and casings to yieldingly retain the latter in their outermost positions with respect to the associated blocks, and means to effect the tilting action of the upper and lower of said blocks and casings when the platen and form are at corresponding elevations.
4. In a paper box machine, the combination with the machine frame, a vertically movable form, and a platen, of paper-folding and pressing devices mounted on said frame, said devices comprising tiltable blocks and casings connected to each other for relative movements, and resilient means interposed between said blocks and the respective casings, and means for actuating said devices to effect the folding of a paper about the edges of a box top section carried on said platen and pressing the paper simultaneously against said top section and the outside surface of a box body section which is carried by said form for the purposes described.
5. In a paper box machine, the combination with a platen for holding in super-
- posed relations a box top section and a cover paper, means to reciprocate and maintain said platen for predetermined times at different elevations, a form adapted to receive thereupon a box-body section, means acting supplemental to the aforesaid means to elevate said form in opposition to its weight and the weight of parts operatively connected therewith, pairs of tilttable paper-folding and pressure devices disposed at different elevations, and means serving to actuate said devices whereby the respective pairs thereof will coöperate with said form and platen to effect the folding and pressing of the cover-paper against both the box-body section and said top section coincidentally when supported by the platen at both the upper and lower positions of the latter.
6. In a paper box machine, the combination with a form adapted to receive a box-body section, a platen arranged to support in superposed relations a box top section and a cover-paper, and means to impart vertical reciprocatory movements to said form and to the platen, of two pairs of devices arranged to coöperate with both the form and the platen to effect the folding of said paper about the edges of said top section and to press the paper against the latter and also against the outer surfaces of said body section, and means to successively actuate said pairs of devices, the last named means serving to cause one pair of said devices to operate once and the other pair to operate twice in each cycle of the operation of the machine.
7. In a paper box machine, the combination with a form adapted to receive a box body section, a platen arranged to support in superposed relations a box top section and a cover paper, and means to impart vertical reciprocatory movements to said form and to the platen, of devices arranged to coöperate with both the form and the platen to effect the folding of said paper about the edges of said top section and to press the paper against the latter and also against the outer surfaces of said body section, and means to actuate said devices twice during the downward travel of the platen and once during the upward travel of the same in each cycle of the machine's operations.

Signed at Seattle, Wash., this 22nd day of June, 1917.
